UNITED STATES PATENT OFFICE.

HARRY FELDBUSH, OF CINCINNATI, OHIO, ASSIGNOR TO WORTHINGTON PUMP AND MACHINERY CORPORATION, A CORPORATION OF VIRGINIA.

CONTROL VALVE FOR COMPRESSOR UNLOADERS.

Application filed April 26, 1920. Serial No. 376,517.

To all whom it may concern:

Be it known that I, HARRY FELDBUSH, a citizen of the United States, residing at Cincinnati, county of Hamilton, and State 5 of Ohio, have invented certain new and useful Improvements in Control Valves for Compressor Unloaders, fully described and represented in the following specification and the accompanying drawings, forming 10 a part of the same.

This invention relates to control or pilot valves of that class used in air compressors for controlling an unloader mechanism by the receiver pressure, the object being to 15 provide a simple and reliable control valve, and especially to provide for the adjustment of the valve to meet different compressor conditions.

In valves of this class, it is important that 20 the valve shall be positive and prompt in both its opening and closing movements, and that there shall be no fluttering of the valve between its fully open and fully closed positions. The valve requirements for such operation, however, will vary in compressors 25 of the same size, and even in the same compressor, under different operating conditions, so that it is important that some means be provided for meeting these varying requirements. This has been done usually by varying 30 the seating surface or travel of the valve, requiring careful manipulation for accurate adjustment and interfering with the reliability and durability of the device. I secure 35 the desired result by a control valve of simple form involving no adjustment of the valve proper, in connection with a regulating valve controlling the fluid passages through the valve, which regulating valve 40 may be of the most simple and convenient form and easy of accurate adjustment, such as an ordinary needle valve.

For a full understanding of the invention, a construction embodying the same in its 45 preferred form, and a modification thereof, will now be described in connection with the accompanying drawing forming a part of this specification, and the features forming the invention then specifically pointed out in 50 the claims.

In the drawings—

Figure 1 is a central section through the control valve in its preferred form;

Figure 2 is a similar section, showing a modification, and

Figure 3 is a sectional plan, with the valve cap removed, the section being on the line 3—3 of Fig. 2, and with parts broken away.

Referring now especially to Fig. 1, A is the valve-casing and B the control valve proper, this valve being shown as a simple cylindrical valve having a close sliding fit in the body A, no provision for leakage past the valve being required. This valve carries at its opposite ends reduced valve extensions 10, 11 in end chambers 12, 13 of casing A, these extensions having, respectively, seats 1, 2 co-acting with corresponding seats 3, 4 on the casing at opposite ends of the valve. Connection to the receiver through 70 pipe C is closed by seat 3, and connection to the atmosphere by seat 4. Receiver pipe C connects through chamber 12 and side passage 15 in casing A with chamber 13 and pipe D leading to the unloader devices, 75 which may be of any suitable type, as well understood in this art. The chamber 12 connects with passage 15 through a restricted opening 5 which is controlled by a regulating valve 6, shown as an ordinary screw 80 needle valve. The valve extension 11 and valve seat 2 are somewhat larger than the valve extension 10 and seat 1, so as to provide for the required pressure drop between inlet and discharge, and valve B is pressed toward 85 its seat 3 to close the receiver pipe C by spring 16 on stem 17 seated in the valve, the tension of spring 16 being preferably adjustable through adjustable bearing screw 18.

The operation of the valve will be understood from the above without extended description, it being understood that when the pressure in the receiver rises to the predetermined point, the receiver pressure, acting through pipe C against the end of valve 95 extension 10, unseats the valve and then produces a quick opening movement of the valve by acting on the larger surface of valve B around extension 10, the flow of pressure air through passage 5 being retarded and 100 regulated by the regulating valve 6, so that the pressure is not transmitted at once to the opposite end of the valve, and the full opening of the valve and its positive seating on seat 4 is thus secured. The unloading action 105 produced by the pressure air passing through

- pipe D now continues until the predetermined drop in pressure in the receiver and pipe C occurs, when the pressure on the unloader end of the valve, aided by the spring 5 16, seats the valve promptly to close receiver pipe C, and open the unloader pipe D to the atmosphere, as shown in Fig. 1.
- The construction shown in Figs. 2 and 3, and its operation, is substantially the same 10 as that of Fig. 1, except that the two valve seats are not in line, but the valve is divided into two parts B' and B² operating in different chambers, these two parts B', B² being connected by lever 19 so as to operate as 15 one valve and secure the same result as in Fig. 1, it being understood that as valve B' lifts from seat 3 to open receiver pipe C, valve B² moves downward or is lowered onto seat 4, to close connection to the atmosphere.
- 20 The parts of the construction other than the valve proper being the same in construction and operation as in Fig. 1, the same references are used for these parts.

It will be understood that, while the valve 25 is especially intended for use as a control valve in unloading compressors, it is applicable also to other uses in which a similar pressure controlled valve is required, and such uses are within the invention.

30 What I claim is:

1. In a control valve of the class described, the combination with a casing having opposed pressure inlet and exhaust valve seats and a port for connection with the 35 valve control mechanism, of a pressure controlled valve device coacting with said seats, a flow retarding passage in the casing connecting the inlet with said port and controlled by the pressure inlet end of the valve 40 device, and a regulating valve in the flow retarding passage.
2. A control valve for air compressor unloaders or the like, consisting of a casing having a pressure inlet and an exhaust outlet, an unloader or other pressure-operated 45 connection, a valve device acting to alternately close and open the pressure inlet and exhaust outlet by its movement in opposite directions, a passage in the casing connecting the pressure inlet with the unloader mechanism connection and controlled by the pressure inlet end of the valve device, and a regulating valve in said passage.
3. A control valve for air compressor unloaders or the like, consisting of a casing having a pressure inlet and an exhaust outlet, a cylindrical valve device therein hav-

ing reduced extensions adapted to close the pressure inlet and exhaust outlet, a port for connection with the unloader mechanism, a 60 passage in the casing connecting the pressure inlet with said port and the exhaust outlet and controlled by the pressure inlet end of the valve device, and a regulating valve in said passage. 65

4. In a control valve of the class described, the combination with a casing having opposed pressure inlet and exhaust valve seats, end chambers adjacent said valve seats within the casing, a port for connection with the valve controlled mechanism, and a flow retarding passage connecting the inlet end chamber with said port at all 70 times, of a pressure controlled valve device co-acting with said seats, and a regulating valve in said flow retarding passage. 75

5. A control valve for air compressor unloaders or the like, consisting of a casing having a pressure inlet and an exhaust outlet, an unloader or other pressure-operated 80 connection, a valve device acting to alternately close and open the pressure inlet and exhaust outlet by its movement in opposite directions, a passage establishing immediate connection between the pressure inlet 85 and the unloader mechanism when the valve is moved to open the pressure inlet on a predetermined rise of pressure therein, and a regulating valve controlling said passage.

6. A control valve for air compressor unloaders or the like, consisting of a casing having a pressure inlet and exhaust outlet, end chambers adjacent said inlet and outlet and within the casing, a cylindrical valve device having reduced extensions adapted 90 to close the pressure inlet and exhaust outlet, a port for connection with the unloader mechanism, a passage connecting the inlet end chamber with said port and the exhaust end chamber at all times, and a regulating 100 valve controlling said passage. 95

7. A control valve for air compressor unloaders or the like, consisting of casing A having opposed pressure inlet and exhaust valve seats 3, 4, a valve device having reduced valve extensions 10, 11 within chambers 12, 13 co-acting with said seats, connection D connecting with the unloader mechanism, passage 15 in casing A connecting chambers 12, 13 with connection D and 110 needle valve 6 controlling passage 15. 105

In testimony whereof, I have hereunto set my hand.

HARRY FELDBUSH.
